UNITED STATES PATENT OFFICE.

WILLIAM G. WALTER, OF PITTSBURG, PENNSYLVANIA.

DESIGN FOR A DRUGGIST'S SIGN.

SPECIFICATION forming part of Design No. 19,260, dated August 6, 1889.

Application filed March 26, 1889. Serial No. 304,893. Term of patent 14 years.

To all whom it may concern:

Be it known that I, WILLIAM G. WALTER, of Pittsburgh, in the county of Allegheny and State of Pennsylvania, have invented a new and original Design for Druggists' Signs, of which the following is a full, clear, and exact description, reference being had to the accompanying drawing, which shows in side elevation a druggist's sign embodying my design.

It consists of a plurality of vessels *b*, *c*, and *d*, each made externally in form of a druggist's mortar, closed, however, at the top, the lowest *b* having a foot *e* and neck portion *f*, the other vessels *c* and *d* being superposed on the vessel *b*, and having contracted portions constituting their bases and necks. The vessels

are of different sizes, the largest being at the base. Around each of the vessels are ornamental bands or zones *g*, constituted of series of raised or embossed convex beads, and at the top of each, adjacent to the contracted neck, is a projection *h*, whose form is that of the handle of a druggist's pestle.

I claim—

The design for druggists' signs, substantially as shown and described.

In testimony whereof I have hereunto set my hand this 13th day of March, A. D. 1889.

WILLIAM G. WALTER.
